ART OF CONVERTING HYDROCARBONS

Vanderveer Voorhees, Hammond, Ind., assignor
to Standard Oil Company (Indiana), Chicago,
Ill., a corporation of Indiana

Application July 10, 1934, Serial No. 734,445

3 Claims. (Cl. 196—70)

My invention relates in general to the conversion of hydrocarbon fluids and more especially to a method and apparatus wherein hydrocarbons to be converted are rapidly raised to an elevated temperature by heat exchange relation with molten material.

In accordance with my invention, molten material, which is utilized as a fluid heating medium, is employed to rapidly increase the temperature of the hydrocarbon under treatment to the desired elevated temperature in a relatively short period of time. The molten material may be heated to the desired elevated temperature, in any suitable manner, such as by passing it either in indirect or direct heat exchange relation with hot combustion gases or by passing it in both direct and indirect heat exchange relation therewith. The thus heated molten material may then be conducted to an enlarged chamber wherein it is maintained in heat exchange relation with a plurality of tubes of relatively small internal diameter therein.

The plurality of tubes having a relatively small internal diameter or cross-sectional area within the enlarged chamber and in heat exchange relation with the molten material therein may be connected together to form a plurality of parallel paths for the hydrocarbon to be rapidly raised to the desired elevated temperature. If desired, each of the parallel paths may comprise a plurality of tubes connected in series, or all of the tubes may be connected in parallel to form the plurality of parallel paths.

A hydrocarbon fluid to be rapidly raised to the desired elevated temperature may be preheated, as for example, by combustion gases produced in the furnace setting and the thus preheated fluid introduced into the tubes of relatively small internal diameter to flow therethrough in the parallel paths.

By providing a plurality of small internal diameter tubes in heat exchange relation with the molten material, a large ratio of heating surface to hydrocarbon fluid volume is made possible. Thus, it will be evident that by dividing the main stream or streams of preheated hydrocarbon fluid into a number of smaller streams, more heating surface is provided for the small quantity of hydrocarbon fluid passing through each path with the advantageous result that the hydrocarbon fluid is rapidly heated to the desired elevated temperature in a relatively short period of time. Moreover, by having the small diameter tubes in heat exchange relation with the molten material, such as being immersed therein, local

overheating of any one part of the tube surface is prevented, which arrangement also permits of imparting large quantities of heat to the fluid being treated without a detrimental temperature gradient between the tube wall and the molten material.

Rapid heating of hydrocarbon fluids is quite desirable in that secondary reactions, which occur upon prolonged conversion of the fluid, are obviated with the result that the formation of tar and gas, and particularly tar, is decreased while more gasoline is produced. This is especially true when converting a higher boiling oil into a lower boiling one, such as gasoline.

My invention also provides for the elimination of the heretofore detrimental low temperature cracking in that the hydrocarbon fluid to be converted is preferably preheated to a temperature short of active cracking and the thus preheated stream divided into a plurality of smaller streams passing in heat exchange relation with the fluid heating medium whereby it is possible to rapidly raise each of the plurality of streams of oil to a high cracking temperature without the disadvantages inherent to the heretofore practiced prolonged low temperature cracking of hydrocarbon fluid. By eliminating prolonged low temperature cracking of the hydrocarbon fluid, a greater proportion of gasoline is produced, as heretofore pointed out, and the thus produced gasoline is much superior to that produced in prolonged low temperature cracking in that desirable anti-knock properties are imparted to the hydrocarbon fluid in heating it to a high temperature in a relatively short period of time.

The heated hydrocarbon fluid upon leaving the tubes in heat exchange relation with the molten material may be immediately quenched and passed to an evaporator or other suitable apparatus for further treatment in a conventional manner or may be soaked at conversion temperature prior to quenching. The molten material, after passing in heat exchange relation with the hydrocarbon fluid flowing through the tubes and preferably in counter current relation to the flow of the hydrocarbon fluid, may be conducted from the enlarged chamber and returned to the heating zone where it is again heated to an elevated temperature.

Comparable results may also be accomplished in accordance with my invention by passing the molten material in counter current direct heat exchange relation with vaporous hydrocarbons. Thus hydrocarbons, preferably in vapor form, may be introduced into the lower portion of an

enlarged chamber and caused to flow in a tortuous path around baffles in the enlarged chamber counter current to descending molten material likewise passing around and over the baffles. By 5 contacting the hydrocarbon vapors directly with the downwardly flowing molten material, excellent heat exchange between the two is accomplished and a large amount of heating surface, molten material, for the volume of oil vapors is 10 made possible, with the result that the hydrocarbon vapors are heated to the desired elevated temperature in a relatively short period of time.

In order to make my invention more clearly understood, I have shown in the accompanying 15 drawings, means for carrying the same into practical effect without limiting the improvements in their useful applications to the particular constructions which, for the purpose of explanation, have been made the subject of illustration.

20 Figure 1 is an elevational view, partly in section, of an apparatus capable of carrying out my invention.

Figure 2 is a sectional view taken along lines 2-2 of Figure 1.

25 Figure 3 is a modified form of construction that may be used in lieu of the structure shown in Figure 2.

Figure 4 is an elevational view, partly in section, of a modification that may be used for the 30 right hand side of Figure 1.

Referring to the drawings and more particularly to Figure 1, there is shown a furnace setting 1, having a combustion chamber 2 and a convection heating chamber 3 separated from 35 each other by a bridge wall 4. The combustion chamber 2 may be provided with a plurality of burners 5 suitably positioned in the lower portion of thereof and adapted to burn any suitable fuel to produce hot products of combustion for 40 the furnace setting.

A supply tank 6, having molten material therein, may be positioned in the upper portion of the combustion chamber and may be provided with an overflow pipe 7 at one end thereof. The molten material from the supply tank overflows 45 through the pipe 7 and may be conducted due to gravity into a suitable wall trough 9 extending along one wall, for instance the back wall, of the furnace. In accordance with my invention, the molten material may be caused to flow 50 spirally around the four walls of the furnace due to gravity and thereafter collected in a suitable reservoir. The trough 9 may therefore be slightly inclined to accomplish the gravity flow of the 55 molten material therein and at the lower end thereof, another similar trough 11, extending along the bridge wall 4, is suitably connected thereto to form a continuous path for the molten material. The trough 11 is likewise inclined to 60 accomplish the flow of molten material and connected to a similarly inclined trough extending along the front wall of the furnace, not shown, which in turn is connected to another similarly inclined trough 12 extending along the end wall 65 of the furnace. The troughs extending along each wall are suitably spaced from each other to absorb radiant heat which strikes the walls of the furnace and extend from an upper part of the combustion chamber 2 to a lower part thereof, thereby forming a spiral path for the molten material. The molten material is thus passed 70 from trough to trough throughout substantially all of the combustion chamber and may be collected in a suitable reservoir 13 positioned in the 75 lower portion of the combustion chamber.

The hot products of combustion from the burners 5 are introduced into the combustion chamber 2 and pass upwardly therethrough continuously imparting heat therefrom both directly and indirectly to the molten material descending in the combustion chamber by means of the spirally arranged troughs. Thus, the molten material collected in each of the troughs and flowing from one to another is subjected to the heat absorbed by the troughs as well as the heat 10 absorbed directly by the molten material. If desired, the molten material may be passed through a coil in the combustion chamber to be heated by indirect heat exchange with the hot gases, or it may be heated entirely by direct contact 15 with the hot gases. A suitable cascade arrangement for heating the molten material may also be provided.

It will usually be desirable to regulate the character of the hot combustion gases, depending on 20 the nature of the molten material employed for heat transfer. For example, where the material is metallic lead it will be desirable to avoid a great excess of air which would oxidize the lead upon contact and produce a slag. Where the molten material consists of a salt which is brought 25 into direct contact with the oil undergoing cracking as hereinafter described, it may be advisable to employ a sufficient excess of air to free the salt from any organic material, coke, 30 etc. which may be carried with it.

The thus highly heated molten material collected in the reservoir 13 may be conducted therefrom through a suitable passage 16 in the bridge wall 4 to a conduit 18 provided at one end thereof 35 or with an inlet pressure pipe 17. As shown in Figure 1, a venturi arrangement 15 may be provided for raising the molten material through the conduit 18. The molten material thus conducted through the passage 16 into the conduit 40 18 may be lifted or raised therein by a suitable inert fluid under high pressure introduced through the pipe 17. The inert fluid under high pressure, which may be highly superheated steam, a suitable gas such as hot combustion 45 gases or high pressure gas from a cracking operation, for example, after fractionating out gasoline, lifts or raises the molten material through the conduit 18 into an elevated tank 19 in an upper portion of the furnace setting. If desired, in lieu of an inert fluid for lifting or raising 50 the molten material to the elevated tank 19, any other suitable means, such as a pump, may be employed. The tank 19 may be provided with a vent pipe 21, controlled by a suitable valve 20, 55 for conducting the inert fluid used to lift or raise the molten material from the tank 19. While the conduit 18 has been shown to the right of the bridge wall, it may be positioned to the left thereof and directly in the molten material 60 collected in the reservoir 13.

The tank 19 is adapted to collect a body of highly heated molten material therein which overflows through a conduit 22 into one end of an enlarged chamber 23, as more clearly shown 65 in Figure 2. The molten material, which preferably fills the enlarged chamber 23 is conducted therefrom into a similar chamber 24 positioned directly therebelow through a conduit 25 at the end opposite the end in which the molten 70 material is introduced into the enlarged chamber 23. Both of the chambers 23 and 24 are preferably maintained full of highly heated molten material which is utilized as a heat transfer medium for imparting the desired heat to hydro- 75

carbon fluids to be converted, as will now be described.

A hydrocarbon fluid to be converted, such as a clean gas oil for example, may be introduced through a line 26 and forced by means of a pump 27 through a preheating coil 28 positioned in the lower portion of the convection heating chamber 3 receiving combustion gases from the combustion chamber 2. The hydrocarbon fluid in passing through the preheating coil 28 may be raised to a temperature short of active cracking and may be conducted by means of a line 29 into a manifold 31. The enlarged chambers 24 and 23 are provided respectively, with a plurality of tubes 34 and 36 of relatively small internal diameter. The tubes in each chamber may be connected together so as to form a plurality of parallel paths, the separate paths being identified by the numerals 34 and 36 with appropriate exponents as shown in Figure 1. The individual tubes of each layer within the enlarged chambers may be connected in series, the tubes 34 of each layer being connected to the manifold 31 by a number of tubes 32, the number of tubes 32 depending on the number of parallel paths formed within the enlarged chamber 24. The plurality of parallel streams of hydrocarbon fluid after passing in heat exchange with molten material within the enlarged chamber 24, preferably accomplished by completely immersing all of the tubes 34 in the molten material, are conducted by tubes 35, the number thereof depending upon the number of parallel paths, into similar parallel paths formed by the tubes 36 in the enlarged chamber 23. The hydrocarbon fluid after passing through the parallel paths formed by the tubes 36 in heat exchange relation with molten material in the enlarged chamber 23 is conducted by means of a plurality of pipes 37, each controlled by a suitable valve 38, into a manifold 39 from which the heated hydrocarbon fluid is conducted by means of a pipe 41, controlled by a valve 42, to any suitable apparatus for further treatment.

The molten material from the enlarged chamber 24 flows through a conduit 43 into the molten material supply tank 6. As shown in Figure 1, the head of molten material maintained in the tank 19 is at a higher elevation than the level of molten material maintained in the supply tank 6 with the result that the molten material, which occupies substantially the entire free area between the tank 19 and the supply tank 6, is forced into the supply tank 6 without the aid of pumps or the like. If desired any suitable means, such as a pump, may be provided for returning the molten material to the supply tank 6 from which it is passed through the combustion chamber 2 to be reheated.

In accordance with my invention there is provided an arrangement whereby it is possible to increase the ratio of heating surface to hydrocarbon fluid volume to a great extent to accomplish rapid heating of the hydrocarbon fluid to the desired elevated temperature. As shown in Figure 1, the hydrocarbon fluid entering the manifold 31 is divided into a plurality of parallel paths, each of which is of considerably smaller internal diameter than the preheating coil. By thus dividing the oil into a plurality of paths and passing it through the tubes 34 and 36 immersed in the molten material in the chambers 24 and 23, intimate contact between the molten material and the tubes is thus obtained to accomplish the advantageous results heretofore pointed out.

In quick cracking it is essential to obtain the maximum area of contact between the hydrocarbon oil and the heating surfaces in proportion to the volume of the oil being treated. In order to use small tubes in practical cracking plant operation it is necessary to operate them in parallel flow in order to obtain any reasonable capacity and reduce the pressures required to force the oil through the furnace. In attempting to carry out this operation in conventional heating equipment by decreasing the diameter of the heating tubes, great difficulty has been encountered with coke formation in the tubes, stopping the flow of oil and resulting in failure of the tubes. According to my invention, by which the small tubes 5 are heated indirectly, it is possible to control the temperature within very much narrower limits than is the case in conventional direct fired tube heaters. The temperature gradient between the molten heat transfer material and the oil tubes 10 is relatively very small, due largely to the heat conductivity of the molten material used. This gradient may amount to only 50 to 200° F., whereas in direct fired heaters the temperature gradient may be as much as 1000° F. With such 15 a low temperature gradient between the heating fluid and the tubes there is substantially no difficulty from local overheating and coking and should coking occur there is no danger of tube failure since the temperature of the heating fluid 20 is not sufficiently high to bring about this undesirable condition.

In Figure 3, there is shown a modified form of enlarged chamber that may be used in lieu of the two chambers shown in Figures 1 and 2. It 25 is to be understood, of course, that only one enlarged chamber may be used in accordance with my invention as illustrated in Figure 1 and where the expression "enlarged chamber" appears in the appended claims, it is intended that 30 such expression covers either one or more enlarged chambers, more especially either of the type of chambers shown in Figure 2 or Figure 3. Referring to Figure 3, there is shown an enlarged chamber 45 provided with a plurality of internal 35 baffles 46 arranged in such a manner as to cause molten material introduced through an inlet line 47 to follow a tortuous path through the enlarged chamber 45 to a suitable outlet 48. In accordance with this modification, a stream of hydrocarbon 40 fluid, preheated if desired, may be introduced through a line 49 into a manifold 51. The manifold 51 may be connected to a plurality of tubes 52 of relatively small internal diameter and the oil introduced into the manifold 51 thus divided 45 into a plurality of streams of relatively small cross-sectional area to be passed through the parallel tubes 52 immersed in molten material within the enlarged chamber 45 to a header 53. The heated oil entering the header 53 being conducted 50 through an outlet line 54 to suitable apparatus for further treatment in any well known manner.

By the arrangement shown in Figure 3 the hydrocarbon fluid to be rapidly heated is passed in 55 a plurality of streams in countercurrent heat exchange relation with the flow of molten material through the enlarged chamber 45 around the baffles 46. Thus rapid heating of the hydrocarbon fluid is accomplished, as before described, 60 and in actual operation it is preferred to accomplish the rapid heating of the fluid in an arrangement comparable with that shown in Figure 3, although countercurrent flow of hydrocarbon fluid and molten material may be accomplished 65

in the arrangement shown in Figure 3. While only a few parallel paths have been shown for both Figures 2 and 3, this is merely for illustrative purposes and the number may be considerably increased. For instance several hundred parallel paths may be provided in accordance with my invention.

Figure 4 illustrates an arrangement whereby it is possible to accomplish the desired rapid heating of the hydrocarbon fluid by direct contact between it and highly heated molten material. The arrangement to the left of the bridge wall 4 shown in Figure 1 has been omitted from Figure 4 as being unnecessary for a proper understanding of this modification, any suitable heating arrangement for the molten material, as above described, being applicable.

Referring more specifically to Figure 4, there is provided an enlarged chamber 55 having a plurality of downwardly extending baffles 56 therein for causing fluids passing therethrough to follow a tortuous path around the baffles. In accordance with this modification, a stream of hydrocarbon fluid, such as a clean gas oil, to be converted may be introduced through a pipe 57 and forced through a preheating coil 58 receiving combustion gases from the combustion chamber 2. The stream of hydrocarbon fluid passing through the preheating coil 58 is raised to a temperature sufficiently high to preferably effect vaporization thereof and the thus vaporized fluid may be introduced through a pipe 59 into the lower portion of the enlarged chamber 55. Molten material is simultaneously introduced into the upper portion of the chamber 55 by means of the pipe 22, which in this modification may be provided with a trap leg as illustrated, and caused to flow downwardly through the enlarged chamber 55 over and around the baffles 56 therein. The vaporous hydrocarbon introduced into the lower portion of the enlarged chamber 55 through the line 59 rises in the enlarged chamber 55 in countercurrent heat exchange relation with the downwardly flowing molten material and due to the direct heat exchange between the two fluids in the enlarged chamber 55, the vaporous hydrocarbon fluid is rapidly raised to the desired conversion temperature and conducted from the enlarged chamber 55, by means of a suitable outlet pipe 61. Both the downwardly flowing molten material and the upwardly rising vaporous hydrocarbon tend to spread out throughout the entire space within the enlarged chamber 55 with the result that a large ratio of heating surface, in this instance direct contact with molten material, to hydrocarbon fluid volume is accomplished which permits of rapid heating of the hydrocarbon fluid.

The molten material after passing in heat exchange relation with the upwardly rising vaporous hydrocarbon may be withdrawn through a conduit 62 and forced by means of a pump 63 to the molten material supply tank 6.

The various elements within the furnace setting have been shown rather diagrammatically and it is to be clearly understood that their arrangement and the relative position of each may be varied without departing from the scope of my invention. It is preferred to position certain of the elements, such as the tanks 6 and 19 as well as the conduits connected to these tanks against one wall of the furnace to thereby prevent any unnecessary obstruction to the flow of hot products of combustion from the combustion chamber into the convection heating chamber 3. The tubes connecting the tubes 36 and 34 in the en-

larged chambers 23 and 24, respectively, to each other as well as to the headers 38 and 39 may likewise be positioned against one end of the furnace setting. It will be evident from the showing, that all of the elements are positioned within the furnace setting which permits of economic operation in that these elements receive intensive heat, including convection and/or radiant heat, which aids in preventing heat loss from the various parts of the system. It is to be understood, however, that my invention may be carried out without arranging all of the various elements within the same furnace setting and obviously some of the elements do not have to be swept or heated by the hot combustion gases and may be suitably lagged to prevent loss of heat.

When applying my invention to the cracking of a relatively clean gas oil, for instance, the oil may be preheated in passing through the heating coil 20 to a temperature as high as about 300° F. or to a temperature just below the active cracking temperature of the particular oil being heated. The thus preheated oil may be conducted to the manifold 31, Figure 1, or the manifold 54, Figure 3, and passed in a plurality of parallel paths through the tubes of relatively small internal diameter connected to the manifold. The molten material collected in the reservoir 13 may be at a temperature of about from 1150° to 1300° F. and conducted through the conduit 18 and tank 19 to the enlarged chambers 23 and 24, or the enlarged chamber 45 of Figure 3, at a temperature substantially the same as that attained during the heating thereof or at a slightly lower temperature. The tubes forming the plurality of parallel paths for the oil are immersed in the molten material and are in direct heat exchange relation therewith. In accordance with my invention these tubes are of relatively small internal diameter such as from about $\frac{1}{8}$ " to $\frac{3}{4}$ ", and preferably about $\frac{3}{8}$ " or $\frac{1}{2}$ " internal diameter. The oil is passed through the plurality of tubes immersed in the molten material in a relatively short period of time, preferably less than 30 seconds, and most advantageously in about two to twenty seconds. The oil in passing through the small internal diameter tubes is rapidly raised to the desired temperature and passed through the tubes while in the active cracking range in a relatively short period of time as above mentioned. It is preferable to keep the temperature of the oil going up and this is efficiently accomplished by the countercurrent flow of the molten material with respect to the oil being converted. The oil is thus rapidly heated to a high temperature of about 1100° to 1300° F. and conducted through either the line 41 of Figure 1, or the line 54 of Figure 3, to suitable equipment, such as an evaporator, for further treatment. It is preferable in operating in this manner to quench the oil in passing through either the line 41 or 54 before reaching the after equipment or if desired, the products may be soaked at cracking temperature before quenching them.

Any suitable pressures may be maintained on the oil being heated. For instance, pressures ranging from approximately atmospheric to as much as 1000 pounds per square inch, or higher, may be maintained on the oil passing through the heating conduits, the selected pressure being reduced after leaving the heating coil by a suitable pressure reduction valve.

While my invention has been specifically de-

scribed in connection with the cracking of a relatively clean gas oil, it is to be clearly understood that other hydrocarbon fluids may also be thermally converted in accordance therewith. For instance, my invention is also applicable to the thermal conversion of normally gaseous saturated hydrocarbons, for the production of gaseous olefins or normally liquid products, and when practicing it in such a manner, temperatures above 1300° and as high as 1600° F. and higher and lower pressures may be employed.

Any suitable molten material may be used in accordance with my invention. For instance, molten lead, or other suitable metal, or any suitable alloy of various metals, or fused salts such as sodium hydroxide or a mixture of fused salts such as sodium and aluminum chloride may be employed. The expression "molten material" used throughout the specification and claims is intended to include any suitable metal, alloy of various metals, salts or mixtures of various salts.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention or exceeding the scope of the appended claims.

What I claim is:

1. An apparatus for the heat treatment of hydrocarbons which comprises a combustion chamber, means for producing hot products of combustion therefor, means within said combustion chamber to enable the heating of molten material partly by direct contact with products of combustion and partly by indirect contact therewith, an enlarged chamber, means for conducting heated molten material to said enlarged chamber, a plurality of conduit elements within said enlarged chamber in heat exchange relation with

molten material therein, said conduit elements being connected to form a plurality of parallel paths, means for introducing hydrocarbon into said conduits wherein it is passed in the plurality of parallel paths in heat exchange relation with the molten material and rapidly raised to an elevated temperature and means for passing the thus heated hydrocarbon from said conduits. 6

2. An apparatus for the heat treatment of hydrocarbons which comprises a combustion chamber, means for producing hot products of combustion therefor, means within said combustion chamber to enable the heating of molten material partly by direct contact with products of combustion and partly by indirect contact therewith, an enlarged chamber having baffles therein, means for conducting heated molten material to said enlarged chamber, means for introducing hydrocarbons into said chamber to thereby cause said hydrocarbons to flow around said baffles in the enlarged chamber and in countercurrent heat exchange relation with molten material introduced into said chamber, and means for withdrawing the heated hydrocarbons and molten material after passing in heat exchange with each other. 10 15 20 25

3. The method of heating hydrocarbon fluids in an apparatus comprising a combustion chamber and a reaction chamber separate therefrom which comprises flowing molten material in a 30 stream in the combustion chamber in both direct and indirect contact with heated combustion gases therein to thereby raise the molten material to an elevated temperature, delivering the thus heated molten material to said reaction chamber, introducing hydrocarbon fluid into said reaction chamber and passing said hydrocarbon fluid in a plurality of parallel paths in indirect heat exchange relation with the molten material to rapidly raise said hydrocarbon fluid to an elevated temperature. 35 40
